PRODUCTION OF TURBINE BLADES

Joseph Lambert Jameson, Betchworth, England

Application February 4, 1953, Serial No. 335,101

Claims priority, application Great Britain
February 4, 1952

9 Claims. (Cl. 51—141)

This invention relates to method and apparatus for the production of turbine and like blades (hereinafter referred to as turbine blades) and especially those having a high length/width ratio with a correspondingly large change in angle along their length, i. e. with a correspondingly large degree of twist from one end to the other: such blades are employed in, for instance, the lower-pressure end of the gas compressors of pilotless missiles and in aero-gas turbines.

The method of producing turbine blades with which the invention is concerned comprises registering a blade work-piece to a preformed die surface having (in obverse) the shape to which the surface of the blade is to be finished and in causing relative movement between the registered workpiece and die and an abrasive band disposed between the juxtaposed blade and die surfaces so that, by pressing the blade and die towards one another, the abrasive surface of the band causes the form of the die surface to be reproduced on the blade surface.

It is of course clear that this method relies on the flexibility of the abrasive band which is required to conform to the surface of the die: the method is entirely satisfactory for most blade forms which have a length/width ratio in which the degree of twist of the blade does not require excessive flexing of the band: when however the method is applied to the production of blades forming the concern of this invention, the large twist over the length of the blade would subject the band to excessive flexure and the band would therefore have such a short working life as to render the method impracticable: such blades would also be difficult to finish by reason of the relatively long length of the blade and its thinness.

Now according to this invention the surface of a blade having a high length/width ratio is formed by the method which consists in registering the blade and the die to one another, in moving between the blade and the die an abrasive band having a width which is only a fraction of the length of the blade and in moving the blade and die on the one hand and the band (at least in that part where it passes between the blade and die) on the other hand relatively in the direction of the length of the blade.

The relative movement can be effected progressively (i. e. continuously) along the length of a blade or alternatively it can be effected in a number of stages in each of which a sectional length of the blade is substantially completed. In this alternative case, the die, the blade and the band will be held registered against movement in the direction of length of the blade, and in each stage the die and blade would be urged towards one another to effect the finishing operation on the corresponding sectional length of the blade.

In some cases, the blade, having been operated on in this way in a number of stages, could be given a final "clean" by causing the blade and die holder on the one hand and the band on the other hand to sweep continuously along the entire length of the blade.

It would in general be preferred to hold the band against

2

movement along the length of the blade and to move the die and the blade holder in that direction, although of course, the converse arrangement could equally well be employed.

5 By this invention the band is required at any one time to flex only to the limited extent required by a fraction of the total twist of the blade. It is also preferred to arrange for the die and blade on the one hand and the band on the other hand to be moved relatively in a plane 10 transverse to the length of the blade, the movement being such that the angle of approach of the band is adjusted to suit the particular angle of twist of that part of the blade upon which it is operating so as thereby still further to reduce flexure of the band: thus the band could approach the blade at an angle such as represents the mean of the twist angle of the blade at points representative of the width of the band.

Thus the band is not subjected at any time to excessive flexure and in addition the blade can be satisfactorily dealt with despite its length and thinness as at any time only part of its total length is being operated upon.

The twist of the blade can be regarded as occurring about an axis which extends lengthwise of the blade and the adjustment of the blade and die on the one hand and 25 of the band on the other hand in the transverse plane could be effected by angular movement about such an axis.

The invention is illustrated in the accompanying drawings in which Fig. 1 is a perspective view of a typical 30 turbine blade of the form with which the invention is concerned and Fig. 2 is an end elevation of such a blade.

Figs. 3-5 are diagrammatic views showing the steps in 35 operation of two forms of the invention, Fig. 6 is a perspective view of a construction embodying one form of the invention, Fig. 7 is a detail perspective view thereof and Fig. 8 is a side elevation of a further detail employed in that machine.

Referring firstly to Figs. 1 and 2, the turbine blade 40 shown has a high ratio of length L to width W and a large change in the angle of twist θ as shown in Fig. 2.

A very efficient way of finishing turbine blades is described in the pending application No. 261,178 and this involves the use of a die having a shape which corresponds (in obverse) to the shape to be reproduced on the blade 45 and also an endless abrasive band which is moved between the surface of the die and the face of a blade which is registered to the die. The abrasive face of the band is presented to the surface of the blade workpiece and its non-abrasive surface is backed by the die so that by 50 moving the die and workpiece towards one another, the abrasive face of the band finishes the blade forming surface of the workpiece to the requisite form.

In Figs. 3-7 the die is shown at 1, the blade or workpiece at 2 and the abrasive band at 3.

55 It will be clear that if an abrasive band 3 of a width approximating to the length of a blade were used to finish the blade along its length, the band would have to flex by an amount approximating to the angle θ and where the angle θ is large the corresponding flexure of the band 3 would also be large and in the result the band would have a short working life.

In accordance with one aspect of the invention this difficulty is avoided in using an abrasive band 3 which is a part only of the length L of the blade, the total length 60 of the blade being dealt with by moving either the band lengthwise of the blade or by holding the band 3 in a fixed location and moving the registered die and blade 1 and 2 in the direction of the length of the blade. In either case the flexure which the band has to undergo at any 65 one time is part only of the total angle θ of twist and hence undue wear of the band is avoided. Moreover, the registration between the die and the blade is not disturbed 70

and this is an important factor in the production of turbine and like blades which are required to be produced with a high degree of accuracy.

The relative longitudinal movement between the band 3 on the one hand and the registered blade 2 and die 1 (this movement being referred to hereinafter as the "longitudinal movement") can be effected continuously, as shown in Fig. 3, or it can be effected in progressive stages along the length of the blade as shown in Figs. 4 and 5.

In Figure 3, the die 1 and blade 2 are shown separated with the abrasive band 3 running between them. The die and blade are moved towards one another and are moved (while maintaining their registration) in the lengthwise sense of the blade, so that the finishing operation on the blade 2 is effected progressively along its length by the fractional width abrasive band. It could be arranged that the die and blade could be moved backwards and forwards along the abrasive band and the feed (i. e. the reduction in the distance separating the surfaces of the die and the blade) could be progressively reduced to the limit required. In Fig. 3 the feed is indicated by the arrow x_1 , the longitudinal movement by the arrows y .

It is however preferred to operate by the method shown in Figs. 4 and 5. In these figures, the die 1 and blade 2 are held against longitudinal movement while a sectional length of the blade 3 is finished, this being illustrated in Fig. 4 where the fractional length l_1 of the blade is being treated by moving by moving the die 1 and blade 2 towards one another as indicated by the feed arrow x_1 . The die and blade are then separated and are then moved together longitudinally as indicated by the longitudinal arrow y_1 . This action presents another fractional length l_2 of the blade 2 for similar treatment by the band 3 as shown in Fig. 5, the feed for this fractional length l_2 being denoted by the arrow x_2 .

In the particular case shown, the blade 2 is finished in two stages although obviously the number of stages can be greater than two as may be found necessary. Whatever be the number of stages it is preferable as is indicated in Fig. 5 to return the parts to their original position while the die and blade are maintained in their position of feed. This movement is indicated by the arrow y_2 in Fig. 5 and by this movement the band 3 is caused to "clean" the entire surface of the blade 2 as a final finishing operation.

A part of a machine for carrying out the preferred operation described with reference to Figs. 4 and 5 is shown in Fig. 6. In this figure the die 1 and a holder 4 to receive a blade 2 are both carried by a support 5 which is itself slidable on guide bars 6 carried by a support 5 carried by the main frame 7 of the machine. The abrasive band 3 is driven by being passed between the surface of a driven drum 8 and a flexible non-abrasive band 9 which itself passes over pulleys 10, 11, 12 of which one is driven. The band 3 is thus trapped between the surface of the drum 8 and the band 9 and so is positively driven, the band passing thence over a guide roller 13, thence through what may be termed a drag box 14 hereinafter referred to, then between the die 1 and the blade 2, and thence via a guide roller 15 to the drum 8.

In the construction shown, the blade holder 4 is caused to be lowered to urge the blade 2 against the abrasive band 3 where that band passes over the die 1; the mechanism for effecting the raising and lowering of the blade holder 4 can conveniently be that described in the pending application No. 261,178 and further description in this specification is therefore believed to be unnecessary except to point out that the blade holder 4 would constitute the blade holder 90 shown in the pending application Serial No. 261,168. In this case the die 1 is fixed against vertical movement but of course to carry the operation described with reference to Figs. 3-5 into effect the support 5 (and hence the blade holder 4 and the die 1) is moved on the slide bars at the appropriate time to effect the longitudinal movement y or y_1 , y_2 .

This longitudinal movement can be effected in any convenient manner as by an hydraulic ram and cylinder arrangement controlled by valves operated in timed relationship with the feed movements x , x_1 , x_2 .

5 The invention also contemplates the step of adjusting the angle of approach or departure (or both) of the abrasive band 3 to or from the die 1 so as to enable the band to be adjusted to suit the angle of twist at the particular part of the blade operated on by the band as it passes along the length of the blade.

10 For this purpose and as applied to controlling the band as it approaches the die, the band 3 passes between rollers 16, 17, 18, 19 in the drag box 14 to or from the space between the die 1 and the blade 2. This drag box

15 is arranged to be raised and lowered as the support 5 is moved longitudinally to present the various parts lengthwise of the blade to the band and the movement of the drag box is chosen so that the endless band is caused to pass between the blade and the die at what may be average

20 twist over that part of the blade being operated upon. To obtain that result, the drag box 14 is carried at the outer end of a frame 20 (see Figs. 6 and 7) which is carried by arms 21 pivoted at 22 on the fixed frame 7. The frame 20 is thus free to rock and so to raise and

25 lower the drag box 14, and the drag box is fitted with a stylus 23 which passes into a control track 24 extending in the sense of the longitudinal movement y . This control track is carried by the support 5 and it is set at such an angle that as the support 5 is moved longitudinally i. e. 30 to produce the movement y or y_1 , y_2 , the drag box 14 is raised and lowered to suit the angle of the blade.

35 As is shown in Figures 6 and 8, the rollers 16 and 18 in the drag box 14 are subjected to the frictional drag effect of a spring 26 which can be regulated by a screw

40 27: by this means the band 3 is maintained flat and is prevented from buckling transversely when the blade 2 and die 1 are moved longitudinally while they are pressed together as for the movement y in Figure 3 or of the movement y_2 , in Figure 4. It may also be set so that

45 when the blade 2 is moved away from the die 1, the band 3 is caused to run with sufficient slackness to prevent its becoming taut over the die when (as is shown) it is of concave form to finish the convex face of a blade and in this way to allow the blade into the concavity. The roller 15 over which the band 3 passes from the die may also be carried by a bracket 28 which is pivoted at its rear end about a vertical pivot so that it can be swung in step with the longitudinal movement referred to to maintain the belt running true.

50 While it is preferred as shown to use an endless abrasive band 3 which is constantly moved in the one direction it would of course be possible to move the band backwards and forwards.

What I claim is:

55 1. Finishing the surface of turbine or like blades by the method which consists in registering the blade to a die having a surface preformed to correspond in obverse to that to be produced on the blade, in disposing between the die and the blade at an angle thereto an abrasive band which has its abrasive face opposed to the blade and

60 which has a width which is a fraction only of the length of the blade surface, in urging the blade and the die towards one another, in relatively moving the registered die and blade and the band lengthwise of the band to cause the abrasive of the band to reproduce on the blade the form of the die where it backs the band, in relatively moving the registered die and blade and the band in the direction of the length of the blade to enable the narrow band to finish the surface length of the blade, and in varying the angle between the band and the die and the blade while relatively moving the die and the blade and the band in the direction of the length of the blade.

65 2. Finishing the surface of turbine or like blades by the method which consists in registering the blade to a die having a surface preformed to correspond in obverse

to that to be produced on the blade, in disposing between the die and the blade at an angle thereto an abrasive band which has its abrasive face opposed to the blade and which has a width which is a fraction only of the length of the blade surface, in urging the blade and the die towards one another, in relatively moving the registered die and blade and the band lengthwise of the band to cause the abrasive of the band to reproduce on the blade the form of the die where it backs the band, in progressively relatively moving the registered die and blade and the band in the direction of the length of the blade to enable the narrow band to finish the surface length of the blade, and in varying the angle between the band and the die and the blade while relatively moving the die and the blade and the band in the direction of the length of the blade.

3. Finishing the surface of turbine or like blades by the method which consists in registering the blade to a die having a surface preformed to correspond in obverse to that to be produced on the blade, in disposing between the die and the blade at an angle thereto an abrasive band which has its abrasive face opposed to the blade and which has a width which is a fraction only of the length of the blade surface, in relatively moving the registered blade and die and the band in the length of the band, in relatively moving the registered blade and die, and the band lengthwise of the blade in a number of steps to register the narrow band with the different lengthwise portions of the blade, in varying the angle between the band and the die and the blade in each stage, and in urging the blade and the die towards one another in each step whereby the band reproduces on the blade the form of the section of the die where it backs the band in each step.

4. Finishing the surface of turbine or like blades by the method which consists in registering the blade to a die having a surface preformed to correspond in obverse to that to be produced on the blade, in disposing between the die and the blade at an angle thereto an abrasive band which has its abrasive face opposed to the blade and which has a width which is a fraction only of the length of the blade surface, in relatively moving the registered blade and die and the band to one another in a first direction lengthwise of the band and in a second direction lengthwise of the blade, and in effecting said movement in said second direction in a number of stages in which the narrow band is registered to the different sectional lengths of the blade, in varying the angle between the band and the blade and the die in each stage and in urging the blade and the die towards one another in each stage.

5. For finishing the surface of a turbine or like blade, apparatus comprising a die holder and a blade holder which are registered to one another, the die holder receiving a die having a preformed surface and the blade holder receiving a blade having its surface registered to the die, means to move the die and blade holder towards and away from one another in successive stages, means training between the holders and transversely thereto an abrasive band having a width which is a fraction only of the length of the blade, means to move the holders and the band relatively lengthwise of the band, means operating to move the holders and the band relatively lengthwise of the blade at each stage whereby the narrow band is caused to operate over the full length of the blade, and means operating finally to move the holders and the band relatively lengthwise of and over the full length of the blade while the holders are urged towards one another.

6. For finishing the surfaces of turbine or like blades, apparatus comprising a die holder, a blade holder, means registering the holders to one another, means training an abrasive band between the holders and transversely to the length of a blade in its holder, the band having a width which is a fraction of the length of the blade, means to move the holders and the band relatively lengthwise of the blade, means to urge the holders towards one another whereby the abrasive band is backed by a section of the die and reproduces over the width of the band the sectional shape on the blade, means to move the holders and

the band relatively lengthwise of the blade to cause the narrow band to traverse the die and the blade, and means to move the holders and the band training means relatively to adjust the angle of the band relative to the die at the different positions of the band lengthwise of the die.

- 5 7. For finishing the surface of a turbine or like blade, apparatus comprising a die holder and a blade holder which are registered to one another, the die holder receiving a die having a preformed surface and the blade holder receiving a blade having its surface registered to the die, means to move the die and blade holder towards and away from one another, means to train an abrasive band between the holders and transversely thereto, the band having a width which is a fraction only of the length of a blade, means to move the holders and the band relatively lengthwise of the band, means to move the holders and the band relatively lengthwise of the blade to cause the narrow band to operate over the full length of the blade, and means to move the band training means and the die holder relatively to one another to adjust the angle of the band relative to the die at the different positions lengthwise of the die.

- 10 8. For finishing the surface of a turbine or like blade, apparatus comprising a die holder and a blade holder which are registered to one another, the die holder receiving a die having a preformed surface and the blade holder receiving a blade having its surface registered to the die, means to move the die and blade holder towards and away from one another in successive stages, means training between the holders and transversely thereto an abrasive band having a width which is a fraction only of the length of the blade, means to move the holders and the band relatively lengthwise of the band, means operating to move the holders and the band relatively lengthwise of the blade at each stage whereby the narrow band is caused to operate over the full length of the blade, means operating finally to move the holders and the band relatively lengthwise of and over the full length of the blade while the holders are urged towards one another, and means to move the holders and the band training means relatively to adjust the angle of the band relative to the die at the different positions of the band lengthwise of the die.

- 15 9. For finishing the surface of a turbine or like blade, apparatus comprising a die holder and a blade holder which are registered to one another, the die holder receiving a die having a preformed surface and the blade holder receiving a blade having its surface registered to the die, means to move the die and blade holder towards and away from one another in successive stages, means training between the holders and transversely thereto an endless abrasive band having a width which is a fraction only of the length of the blade, means for driving the band, means to move the holders and the band relatively lengthwise of the band, means operating to move the holders and the band relatively lengthwise of the blade at each stage whereby the narrow band is caused to operate over the full length of the blade, means operating finally to move the holders and the band relatively lengthwise of and over the full length of the blade while the holders are urged towards one another, and means to move the holders and the band training means relatively to adjust the angle of the band relative to the die at the different positions of the band lengthwise of the die.
